UNITED STATES PATENT OFFICE.

FREDRICK S. DICKINSON, OF NEW YORK, N. Y.

DESIGN FOR A TIRE-CASING.

58,182.

Specification for Design. Patented June 21, 1921.

Application filed January 23, 1920. Serial No. 353,578. Term of patent 14 years.

To all whom it may concern:

Be it known that I, FREDRICK S. DICKINSON, a citizen of the United States, and resident of New York, in the county and State of New York, have invented a new, original, and ornamental Design for Tire-Casings, of which the following is a specification, reference being had to the accompanying drawing, forming part thereof.

Figure 1 is a plan view of a portion of the tread of a tire casing, showing my new design.

Fig. 2 is a cross-section on the line 2—2, Fig. 1.

Fig. 3 is a cross-section on the line 3—3, Fig. 1.

The features of my design comprise a central ridge extending circumferentially of the tread of the tire casing and connected by cross-webs or ridges with the respective sections of a series of surface blocks or ridges extending circumferentially on each side of said center ridge, the ends of all said ridges being parallel and said connecting cross-webs of the respective side series being in staggered or alternate position with relation to the transverse plane of the tire, and the

respective side series of outer surface blocks being also in relative staggered position. The respective outer series of surface blocks or ridges are separated from the intermediate center ridge by grooves or depressions which are separated by said cross-webs and are thus in staggered relative position, and said outer series surface blocks or ridges are also separated by intermediate grooves or depressions which extend diagonally or at an angle to the transverse plane of the tire and intersect the grooves or depressions which separate said blocks from the center ridge, the diagonal grooves or depressions at the respective opposite sides being in the same direction transversely of the tire, but not in the same cross-plane, and being thus on different parallel planes and respectively staggered with relation to the transverse plane of the tire.

I claim:

The ornamental design for a tire casing, substantially as shown.

In testimony whereof I have signed the foregoing specifications.

FREDRICK S. DICKINSON.
